DIAMOND HOLDER OR DOP FOR HOLDING
DIAMONDS

Leopold Bartnovsky, New York, N. Y.

Application March 3, 1945, Serial No. 580,743

6 Claims. (Cl. 51—229)

This invention relates to diamond holders or so-called "dops" for holding diamonds while the same are being ground or polished, and the primary object of the invention is to provide a device of this character by means of which speed and accuracy in polishing diamonds may be attained.

As is well understood in this art, the grinding and polishing of the various facets on a diamond to uniformly correct angle and shape is of paramount importance and this requires extreme watchfulness on the part of the workman, who is constantly required to repeatedly elevate the work from the polishing wheel to note progress of the grinding and polishing operation. The present invention contemplates the provision of means by which uniformity of operation for each of the facets is assured since a signal means is provided by which the completion of the grinding and polishing operation on a facet is at once indicated to the operator who can then adjust the diamond to position for grinding and polishing of the next facet.

More particularly, the invention contemplates the provision of a holder having an adjustable contact finger adapted to be so positioned that its extremity will be located at a predetermined point on a diamond held by the holder, such as at the girdle of the stone, whereby the extremity of the finger will be brought into contact with the surface of the polishing wheel when the facet being formed will be ground to the required angle. The invention includes the provision of a suitable signal device, such as a small electric light, and an electric circuit therefor which will be closed to ignite the light when the contact finger is brought into contact with the surface of the polishing wheel, thus indicating that the grinding or polishing of a facet on the stone has been completed.

An object of the invention is to provide in a device of this character means by which the contact finger or "feeler" may be easily and swiftly adjusted to the correct point and by which the finger may be retracted to permit release or resetting of the diamond on its seat, yet may be at once replaced in its former setting without adjustment.

These and other objects are accomplished by the invention, a more particular description of which will be hereinafter set forth and pointed out in the claims appended hereto.

Reference is to be had to the accompanying drawing, forming a part hereof, in which Fig. 1 is a side elevation of the holder, constructed in accordance with the invention; Fig. 2 is a front view of the same; Fig. 3 is a view of the contact

finger mechanism, with a portion of the guide being shown in section, and Fig. 4 is a side view of the finger removed from its guide means.

In the drawing the body or head of the holder 5 or dop is indicated at 1, the same being provided with a projecting stem 2 by means of which the holder is supported at the proper angle at the end of the supporting arm 3. The diamond to be ground and polished is shown at 6, the same being held against a seat 5 formed on a stem 4 which is adjustable in the body of the holder in any suitable manner to thereby properly locate the seat to hold a diamond of any given size in position to be ground and polished by a polishing wheel, a portion of which is diagrammatically indicated at 30 in Fig. 1. The diamond 6 is held against the seat 5 by means of a pair of curved fingers 7, at least one of which is adjustable by means of the screw 24. These fingers 7, in co-operation with the flange 23 on the seat, hold the diamond in position against the seat.

The body 1 of the holder is provided with a flat face 31, and secured thereto by means of the screws 9 is a guide member 8. Extending through the guide member 8 is a passage 10 through which a threaded rod 11 is axially slideable. Said rod 11 has a fixed head 12 at one end and is split at its opposite end to accommodate a spring finger 19a, the finger being secured in the split portion of the rod by means of the rivets 20, whereby it projects beyond the end of the rod in the manner clearly seen in Fig. 4.

Threadably received in one end of the passage 10 is a bushing 15 through which the rod 11 is slideable, and confined between the inner end of the bushing 15 and a sleeve 17 secured on the rod 11, is a coil spring 16 which tends to urge the rod out of the opposite end of the passage to an extent permitted by stop means 13 adjustable on the rod 11. Said stop means consists of the nut 13, adjustable on the threaded part of the rod 11, and it includes also a lock nut 14 which holds the adjustment of the nut 13 in any desired position. A pin 18 extends through the bushing 17 and through the rod 11 and said pin may be employed to fasten the bushing 17 to the rod. Said pin is provided with a projecting part 19 extending laterally from the sleeve or bushing 17 and movable in a slot 21 formed in the wall of the guide member 8 and seen in Fig. 2.

Located in the slot 21 is a catch or detent 22 adapted to engage around the projecting part 19 of the pin when the rod 11 is manually drawn to a retracted position and hold the same re-

tracted against the pressure of the spring 16, as will be explained.

From the foregoing, the operation of the device will be readily understood. A diamond 6 is placed upon the seat 5 and held thereon as previously described. By rotation of the adjusting nut 13, while the lock nut is in a retracted position, the rod 11 may be advanced or retracted through the passage 10 to thereby position the tip or extremity of the spring contact finger 19a right at the girdle of the diamond, or at such point desired to limit the grinding or polishing operation. When this adjustment has been secured, the lock nut 14 is turned to bring it against the nut 13 and thereby hold the position of the latter nut. The device is then ready for operation and the arm 3 is lowered to bring the diamond 6 against the rotating polishing wheel 30. The polishing operation continues until the tip or extremity, which may be of knife-edge form, of the finger 19a comes into contact with the surface of the polishing wheel, this serving to actuate a signal to indicate to the operator that the grinding of the facet has been completed.

The signal means is diagrammatically illustrated in Fig. 1, and it may consist of a small, conveniently placed electric lamp 25, connected at 26 to a battery 27 or other suitable source of current. The other side of the battery connects to a suitable portion of the frame of the polishing machine so that the wheel 30 is thereby included in the circuit. The holder 1, or the arm 3 to which the holder is attached, is connected to the lamp 25 so that it will be apparent that when the finger 19a contacts the wheel 30, circuit will be closed between 28 and 29 to illuminate the lamp and indicate to the operator that the grinding of a facet to the proper angle has been completed.

When it is desired to shift the diamond to present another portion of it to the wheel 30, the spring finger 19a is moved out of the way or retracted. This is done, and without losing the adjustment of the finger, by grasping the head 12 and drawing the rod 11 out until the pin 19 is engaged by the detent 19. This engagement of the pin by the detent will cause the rod to be held in a retracted position against the pressure of the spring 16, until the diamond has been placed in position for the grinding of the next facet, whereupon a slight push on the head 12 will cause the pin 19 to be moved past the detent 22 and allow the finger to be thrust forward under the pressure of the spring 16 to the extent determined by the previously adjusted stop 13. In view of the fact that a once-secured adjustment is maintained, yet a release of the contact finger from its advanced position is quickly obtained, the device will insure the grinding of all of the facets of a stone to a uniform depth of cut, with but little attention on the part of the operator.

What I claim is:

1. In a diamond holder or dop, a seat against which a diamond is held, a guide on the holder, a threaded rod axially adjustable through said guide, a spring contact finger at one end of the rod and projecting from the guide and adapted to have its end located in a predetermined position relative to a diamond held against the seat,

spring means surrounding the rod and acting to urge the finger toward the diamond, and at least one adjusting nut on the rod to determine the extent to which the finger is urged by the spring means toward the diamond to indicate a point to which the diamond shall be ground.

2. In a diamond holder or dop, a head having a seat against which a diamond is held, means for holding the diamond against the seat, a guide 10 secured on the head, a rod slidable through the guide, a spring finger on said rod and projecting out of the guide to enable its end to be positioned as a predetermined point on the diamond held against the seat, a threaded portion on the rod, nuts adjustable on the rod to serve as stops thereon to limit the axial sliding movement of the rod through the guide in a direction toward the diamond, a spring for urging the rod toward the diamond to an extent permitted by the stops, and 20 catch means for holding the rod in a retracted position against the pressure of the spring.

3. In a diamond holder or dop, a seat for holding a diamond, a guide located adjacent to the seat, a rod axially movable through the guide, a spring finger on the rod constituting an electrical contact member and adapted to have its end positioned at a predetermined point on the diamond by projection of the rod out of the guide for a selected distance, rotative adjustment means on the rod for axially adjusting the rod through the guide, spring means for urging the rod toward the diamond to an extent permitted by the adjustment means, means for permitting manual retraction of the rod through the guide and a detent for holding the rod in a retracted position.

4. In a diamond holder or dop as called for in claim 3, including signal means, an electrical circuit for actuating said signal means, the diamond holder being so connected into said circuit together with the polishing wheel against which it holds a diamond, that contact of the spring finger with said wheel will close the circuit to actuate the signal means.

5. In a diamond holder or dop, a seat against which a diamond is held, a guide on the holder, a threaded rod slidable through the guide, a spring contained within the guide, a shoulder on the rod against which the spring is operative to urge the rod in a direction toward the diamond held against the seat, an adjustable stop on the threaded portion of the rod, a projection extending laterally from the rod, the guide having a slot in which said projection is movable, a detent located in the slot for engagement with the projection when the rod is moved to a retracted position against the pressure of the spring, and a contact finger carried at one end of the rod and adapted to be positioned at a predetermined position relative to the diamond held against the seat, by axial adjustment of the rod through the guide.

6. A diamond holder or dop as called for in claim 5 and including an electrically actuated signal, and an electric circuit connected thereto and which circuit is closed to actuate the signal when the contact finger is brought against the surface of a polishing wheel against which the diamond is held by the holder or dop.

LEOPOLD BARTNOVSKY.
